UNITED STATES PATENT OFFICE.

IRA A. MANN, OF PITTSBURGH, PENNSYLVANIA.

DESIGN FOR A BOWL-BASE FOR LAVATORIES.

46,438.

Specification for Design.

Patented Sept. 22, 1914.

Application filed May 18, 1914. Serial No. 839,451. Term of patent 14 years.

To all whom it may concern:

Be it known that I, IRA A. MANN, a citizen of the United States, residing at Pittsburgh, in the county of Allegheny and State of Pennsylvania, have invented a new, original, and ornamental Design for a Bowl-Base for a Lavatory, of which the following is a specification, reference being had to the accompanying drawing, forming part thereof.

Figures 1 and 2 are respectively perspective and front elevation views of a lavatory, the full lines showing the bowl base in

which my invention resides, and the dot and dash lines showing a conventional form of lavatory top forming no part of my invention.

I claim:

The ornamental design for a bowl base for a lavatory.

IRA A. MANN.
